UNITED STATES PATENT OFFICE.

ADAM ZISKA, JR., OF MILWAUKEE, WISCONSIN, ASSIGNOR TO MILWAUKEE PRESS & MACHINE COMPANY, OF MILWAUKEE, WISCONSIN.

CROSSHEAD PITMAN CONNECTION.

1,397,308.

Specification of Letters Patent. Patented Nov. 15, 1921.

Application filed March 22, 1920. Serial No. 367,846.

To all whom it may concern:

Be it known that I, ADAM ZISKA, Jr., a citizen of the United States, and resident of Milwaukee, in the county of Milwaukee and State of Wisconsin, have invented certain new and useful Improvements in Crosshead Pitman Connections; and I do hereby declare that the following is a full, clear and exact description thereof.

10 My invention relates broadly to new and useful improvements in punch press and similar machines, and particularly to an improved type of pitman connection for the tool carrying cross heads thereof.

15 As at present constructed the pitman connection in this type of machine is extensible and contractible so as to move the tool carrying cross head different distances away from the actuating crank. However, the parts of such pitman connections are so arranged with respect to each other that the construction is relatively non-rigid with the result that considerable wear takes place and lost motion usually occurs. This is very detrimental to the efficient operation of the several parts of the machine.

Consequently it is the primary object of this invention to provide a simply constructed extensible and contractible pitman connection which will overcome these several disadvantages and will be much more efficient in other ways than the similar devices of ordinary construction. In other words the improved structure is rigid so that stripping action is prevented which eliminates motion between the different parts, and is strongest in the center where the greatest strain occurs.

A further object of the present invention is to provide an extensible and contractible pitman having means for pivotally connecting one end of the same to a usual tool carrying cross head, the connection between said end and said means being such that the punch strains imparted to the cross head are evenly distributed and transferred to the pitman.

With these general objects in view the invention resides in the novel features of construction, combination and arrangement of parts which will be hereinafter more particularly described and claimed and shown in the drawing wherein:

Figure 1 represents a vertical sectional view through a cross head and illustrating

the manner of connecting the same with a crank by means of my improved pitman, parts of the latter being broken away and in section, and

Fig. 2 is a detail horizontal section taken 60 on the plane of the line 2-2 of Fig. 1.

In the accompanying drawing only so much of a punch press machine is illustrated as to show the application of my invention thereto, and in said illustration the 65 reference character 1 denotes a tool carrying cross head adapted to be reciprocated in suitable guides by means of the rotation of a crank or the like 2. The pitman connecting the cross head and the crank forms the 70 basis of the present invention.

Said invention includes a pitman proper 3 comprising an internally threaded sleeve 4 open at one end to receive a threaded stem 5 and having a crank bearing at its other 75 end. This bearing consists of a sleeve carried portion 6 and a cap piece 7, these parts being secured together and around the crank 2 by means of clamp screws 8. The threaded stem 5 is designed to be moved into and 80 out of the sleeve 4 by rotating the same in appropriate directions. The lower or open end of the sleeve 4 is split at one side as at 9 and adjacent thereto are formed clamp ears 10 through which a clamp bolt 11 extends. Thus by tightening the bolt 11, the stem 5 may be locked within the sleeve after it has been disposed in predetermined relation thereto.

The outer or lower end of the stem 5 is 90 shaped to provide a frusto-conical head 12 and a circular radially extending bearing flange 13, the latter being spaced inwardly of the former and positioned between the same and the end of screw threads on the 95 stem 5. The periphery of the flange 13 is provided with a plurality of radially extending sockets 14, in one of which a suitable instrument may be inserted for the purpose of rotating the stem 5.

The lower side of the flange 13 forms a bearing surface for contact with a flat surface formed on one face of a two part connector plate 15, the same also having a socket 16 of frusto-conical shape, the opening of 105 which is surrounded by said flat surface. Entrance into this socket 16 is attained by the removal of the separable section 15' of the two part connector plate so that the head 12 may be disposed in or removed from 110

the socket. The separable section 15' has a channel 17 receiving a shoulder 18 formed on the main section of the connector plate, and the two parts of the latter are secured 5 together by retaining screws 19 which are threaded through cooperating bosses 20 as shown in Fig. 2.

The main section of the connector plate has a depending bearing 21 which is located 10 between bearing ears of the tool carrying cross head 1 and is pivoted thereto by means of a pin or the like 23. The lower end of the pitman is thus rotatably and pivotally connected with the cross head 1. In use the 15 flange 13 always remains in engagement with the flat face of the connector plate, and as a result receives the punch strain imparted to the cross head. However, regardless of this engagement between these parts, 20 the stem 5 may be readily rotated within the sleeve 4 when the clamp screw 11 is loose with a consequent adjustment in length of the pitman.

Various minor changes may be made in 25 the form and proportions of the different parts of the invention without departing from or sacrificing any of the advantages thereof.

I claim:

30 1. A machine of the class described, a tool carrying member, a crank, and means connecting the same including a connector plate pivoted to the tool carrying member, an extensible and contractible member having one 35 portion connected with the crank, the member being lengthened and shortened by rotating a second portion in the first mentioned portion, the second portion having a flat bearing surface and a frustoconical 40 head projecting from the central part thereof, said connector plate having an annular internal flange with a flat surface engaging said first mentioned flat surface and an inclined surface engaging the inclined surface 45 of the frustum.

2. In a machine of the class described, a

tool carrying member, a crank, and means connecting the same including a two part connector plate having a flat bearing surface surrounding a socket therein, one part of 50 the plate being removable to provide access to the socket, an extensible and contractible member having one portion connected with the crank, the member being lengthened and shortened by rotating a second portion in 55 the first mentioned portion, a head on said second portion of the extensible and contractible member and rotatable in said socket, said head being disposed therein when the removable part of the connector plate is 60 separated from the main part, and a bearing flange having a flat face extending from said second portion of the extensible and contractible member and disposed in contact with the flat bearing surface of the connector plate. 65

3. In a machine of the class described, a tool carrying member, a crank, and means connecting the same including a two part connector plate pivoted to the tool carrying 70 member and having a flat bearing surface surrounding a socket therein, one part of the plate being removable to provide access to the socket, an internally threaded sleeve open at one end and having its other end 75 connected with said crank, a threaded stem disposed in said sleeve and having a portion projected therefrom, a head on the projected end of the stem and rotatably disposed in said socket, said head being positioned in said socket when the separable portion of the connector plate is removed, and a flange extending radially of said stem, said flange having a flat face for engagement with the bearing surface of the connector plate. 80 85

In testimony that I claim the foregoing I have hereunto set my hand at Milwaukee, in the county of Milwaukee and State of Wisconsin.

ADAM ZISKA, JR.
